DEVICE FOR DISCHARGING PASTY, VISCOUS OR LIQUID SUBSTANCES

Filed July 31, 1933

UNITED STATES PATENT OFFICE

2,012,396

DEVICE FOR DISCHARGING PASTY,
VISCOS OR LIQUID SUBSTANCES

Charles Elmer Luce, Stuttgart, Germany

Application July 31, 1933, Serial No. 683,054
In Germany July 12, 1933

3 Claims. (Cl. 221—78)

This invention relates to a device for discharging pasty, viscous or liquid substances.

Hitherto it has been customary to discharge pasty, viscous or liquid substances in predetermined or adjustable quantities from tubular containers composed of tin, aluminium or some other suitable flexible or compressible metal, the container being provided with a nozzle for the discharge of the contents thereof, and with a cap 10 acting as a stopper. These containers or tubes are discarded when empty but they are too expensive, in relation to the value of the contents, to be so discarded, and the purpose of the present invention, therefore, is to reduce the cost of such 15 tubes or containers to a very marked extent.

This is, according to the present invention, essentially effected by the fact, that the container or tube is designed as a quite simple and extremely cheap component part of the device, 20 whereas the more costly device which enables the quantity of the mass or contents to be regulated at will is a separate individual component part. Its design is such that it is adapted to be rapidly and without much trouble, affixed to any 25 cartridge or container. This arrangement makes it possible for the manufacturer to supply only the cartridge or tube proper, and for the distributor or retailer only to stock these comparatively inexpensive cartridges, while on the other 30 hand the purchaser or user requires only once to buy the part provided with the discharge nozzle and designed as the head of the cartridge, and has on future occasions to buy the cartridges only, which are composed of an extremely cheap 35 material, and can consequently be thrown away when they are empty without any appreciable loss.

These cartridges may be constructed either as 40 collapsible tubes or as rigid sleeves. It is possible to use, for instance, paper coated with a fibre free cellulose acetate film as a suitable material for the said cartridges, or they may have the cellulose acetate or the like applied to them 45 in the form of a coat of paint, or an insertion of a metallic foil may be used, thus making the same cartridges moisture-proof and grease-proof.

In order that the said invention may be clearly understood and readily carried into effect, the 50 same will now be described more fully, by way of example, with reference to the accompanying drawing, in which:—

Figure 1 shows an unused empty cartridge, with the nozzle head.

Figure 2 is a front view, and Figure 3 a sec-

tional view, showing the cartridge in the form of a tube.

Figure 4 is an inverted plan view of the tube.

Figure 5 is a sectional view, and Figure 6 is a 5 cross section, showing the cartridge in the form of a sleeve.

Figure 7 is a front view of a stand or support for sleeve shaped cartridges.

Figures 8 and 9 are views, one in section and the other in elevation, of the upper tube parts; 10 in another embodiment, one open and one closed, and

Figure 10 is a cross section thereof.

Referring to the drawing, there is provided a cylindrical cartridge *a* adapted to accommodate 15 the pasty mass or fluid and equipped with a head *b* (Figure 1) serving for the discharge of the contents in regulatable quantities. The cartridge *a* may be in the form of a collapsible tube (Figures 2-4) or it may be designed as a solid or rigid 20 sleeve adapted to withstand severe handling (Figures 5-7).

The cartridge is made of extremely cheap material such as, for instance, paper, which has been rendered water-proof and grease-proof by means 25 of an application either on one or both of its surfaces, or by painting it on either one or both of its surfaces, with a coat or film *c* of fibreless acetate cellulose (Figure 3) or by means of inserting a suitable metal foil *d* (Figure 5) between 30 two layers of paper. Should it be desired, other substances may be used having the same properties. It is an essential condition that the material used for the cartridges should be collapsible and adapted to be pressed together when emptying the tubes and folded over in a manner known 35 per se.

The cartridges *a* are, after having been filled, adapted to be closed at their upper extremities by means, for instance, of a cork stopper *e*. These 40 cartridges *a* are in principle designed with certain predetermined external diameters, so that the head *b* can be affixed on any of the cartridges *a* of the corresponding size. In regard to the embodiment shown in Figures 1-7, the head *b* 45 is mounted on the extremity of the cartridge *a* as a lid or cover, whereas it is screwed into the cork stopper *e* in the embodiment shown in Figures 8-10.

In the first-mentioned embodiment, the said 50 head is provided at its downwardly extending flange, for instance, with a fine gauge internal screw thread, which, as the head *b* is being screwed on to the cartridge, presses into the comparatively soft material thereof. The head 55

b is provided at its bottom side with a projection f having a through passage or channel g provided in it, which latter opens or leads into the discharge orifice h of the nozzle i. A cap 5 k can be mounted on the nozzle in such a manner as to be partially rotatable relatively thereto. The said internal projection f is also provided with a screw thread, and terminates in a cutting edge l which serves the purpose of perforating the cover m serving to shut off the passage of the stopper e of the finished cartridges, as the head b is being fixed on the cartridge a.

In the embodiment shown in Figures 8-10 the head b consists only of the projection f and the nozzle i. In this case, the discharge orifice h is provided on the side and is shut off by the yieldable material of which the cork e is composed, when the head b is screwed home sufficiently. If the contents of the cartridge are to be discharged, the head b is unscrewed until the discharge orifice is uncovered.

When the cartridges a are used as collapsible tubes, they are pressed together at their lower extremities and folded over, the folded over extremity being retained thus folded, by means of a clamp, which may, for instance, consist of a suitable pliable metal; at both ends of the said clamp lugs o are provided which are bent around the folded over part of the tube, thus securely holding the various folded over layers together.

In the rigid constructional form of the cartridges a shown in Figures 5-7, their contents are forced out by means of a piston p which is drawn through the cartridge a from the lower extremity upwards. This piston p serves with the rigid cartridges a at the beginning as a closing device. The said piston is, in the constructional form shown, drawn or pulled inwards, by means of an external handle q, the spindle r of which is in as close proximity to the nozzle i as possible, and extends transversely through the cartridge a, being preferably rotatably mounted and passing through the top cork stopper e of

the said cartridge. A catgut string s or the like is fixed to the said spindle r, said string being connected to the piston p and wound on the spindle r of the handle e, thus permitting the piston p to be moved relatively to the cartridge a (Figure 5).

When the cartridge is of the rigid type, it can be used alone, or it may, as shown in Figure 7, be mounted in a suitable stand.

The said stand may consist of a rigid outer sleeve t provided with a base u into which the cartridge a is introduced from the top. An incision or notch v is provided for the neck of the handle q, the said notch being preferably of an angular shape, or provided with a lateral rest 15 or stop w, so as to prevent any inadvertent removal of the cartridge a from the tube t.

What I claim is:—

1. A device for dispensing fluent substances comprising a tubular container of substantially no value when empty, a plug in one end of said container traversed by a passage, a piston in the container, means supported in the plug to operate the piston to contract the volume between the same and the plug, a seal closing the mouth of the passage, a nozzle head having a flange engageable with the plug end of the container, and a nozzle tube on said head adapted to puncture the seal and to enter the passage when the head is applied to the container. 30

2. A device according to claim 1, in which the means includes a spindle having a handle and a string secured at one end to the piston and the other end around the spindle.

3. A device according to claim 1, in which the means includes a spindle having a handle and a string secured at one end to the piston and the other end around the spindle, and in which a stand is provided for the container as a rigid outer sleeve having a notch therein in which the spindle is provided to prevent inadvertent removal of the container from the stand. 35 40
